UNITED STATES PATENT OFFICE.

WILLIAM C. KRAUSE, OF MILWAUKEE, WISCONSIN.

BRANDING IRON.

Application filed May 7, 1923. Serial No. 637,071.

To all whom it may concern:

Be it known that I, WILLIAM C. KRAUSE, a citizen of the United States, and resident of Milwaukee, in the county of Milwaukee, and State of Wisconsin, have invented certain new and useful Improvements in Branding Irons; and I do hereby declare that the following is a full, clear, and exact description thereof.

10 This invention relates to branding machines and is particularly directed to an electrically heated branding machine.

Branding machines heretofore constructed have not been wholly satisfactory as they 15 were either supplied with a fixed insignia bearing plate or else it was necessary to carry in stock a plurality of fully equipped plates with the particular legend engraved thereon. Obviously, therefore, when any 20 change was desired, it was necessary to form a wholly new plate and to adapt the plate to the particular requirements of the heating iron.

This invention is designed to overcome 25 the above noted defects, and objects of the invention are, therefore, to provide a branding machine in which the individual letters may be assembled in a position to be effectively heated by the heating elements, in 30 which any desirable combination of letters or insignia may be had, and in which the changes required to effect these combinations may be most readily and easily made.

Further objects are to provide a branding 35 machine in which the heat is applied at the exact point needed so that the minimum travel of heat is required to thereby increase the efficiency of the apparatus and decrease the time required to bring 40 the iron up to the branding temperature.

Further objects are to provide a branding iron in which the operators hands are 45 fully shielded from excessive heat, in which maximum facility is afforded in manipulating the device, and to provide a device in which the parts are fully protected against damage.

Embodiments of the invention are shown 50 in the accompanying drawings, in which:—

Figure 1 is a side elevation partly in section of the preferred form of the device.

Figure 2 is a sectional view on the line 2—2 of Figure 1.

Figure 3 is a modified form of branding 55 plate.

Figure 4 is a side elevation partly broken away of a further form of the invention.

Figure 5 is a sectional plan view on the line 5—5 of Figure 4.

Figure 6 is a face view of the platen with 60 the type arranged thereon, a part being broken away to illustrate the construction.

The main body of the device comprises a backing plate 1 of metal which may be provided with any number of rectangular 65 grooves 2, in the form shown in Figures 1 and 2, two grooves being employed. This body portion 1 has the platen 3 clamped thereto by means of screws or similar devices 4, so as to provide between the upper 70 flat face of the platen and the bottom of the grooves 2, a protected channeled area. Within this channeled area heating elements 5 of any desired form are positioned. These heating elements may conveniently consist 75 of flattened spirals of a heating wire suitably wound upon an insulating core and surrounded by proper insulating material.

The platen is provided with longitudinal 80 grooves therethrough, the side walls of which are undercut as indicated at 6. A plurality of metal type 7 are provided with outwardly projecting flanges 8 adapted to be slid into the undercut or grooved side walls of the main grooves and to thereby be maintained 85 in position and in intimate contact with the surface of the platen 3.

The type may conveniently be held in place by means of relatively thin end members 9 which are similarly equipped with 90 flanges 10 and are each provided with a set screw 11 so that they may be locked in position and hold the type in their properly assembled relation.

It is to be noted that these locking members 9 do not project outwardly beyond the outer face of the platen 3 so that the raised portions 12 of the type constitute the sole projecting portions of the apparatus.

A handle 13 carried in an inverted U-shaped frame 14 is provided. The frame is secured in position by means of screws 15 which pass through the bottom portion of the frame and through insulating heat resisting pillars 16 and a similar heat resisting plate 17. The members 16 and 17 are preferably also heat insulators.

Although the individual type are used in the preferred form of the invention, a solid die plate 18 (see Figure 3) may be employed 110

and is provided with rows of elevated type or other insignia 19 adapted to be positioned directly beneath the heating element. Suitably threaded apertures 20 are provided for the reception of the ends of the screws 4.

Figure 4 shows a further form of the invention in which the platen 21 is provided with a plurality of grooves provided with undercut walls, as previously described, for the reception of type or other insignia bearing members 22 and locking plates 23 similar to the members previously described. This platen is secured to the body member 24 and a plurality of longitudinally extending heating elements 25 are positioned directly over the type receiving grooves, and frame plates 26 are secured to the body portion and carry frame members 27 which project upwardly therefrom. The upper ends 20 of the frame or members 27 are connected by links 28 to a lever 29. The lever may be pivoted, as indicated at 30, to any fixed support and may, if desired, be provided with a spring 31 to normally retain the branding device in an elevated position.

The electric leads for supplying current to the apparatus may be connected thereto in any suitable manner. As shown in Figure 1, the supply leads 32 may pass through a suitable bushing 34 and from thence into the body of the device.

In Figure 4, the leads 33 are connected to the various heating elements by means of transverse end conductors 35 insulated from the body portion by suitable insulating blocks as shown.

It will be seen that a branding machine has been provided in which maximum protection for the operator is afforded, in which heat is generated at the exact places needed, in which the travel of the heat is extremely short, and in which any desired combination of individual letters may be made.

This type of branding machine is admirably adapted for branding articles in a permanent manner and also for providing means for ready changing of the branding marks to the exact needs of the user, thereby avoiding the necessity of carrying in stock a large number of branding plates.

I claim:

1. A branding machine comprising a channeled body portion, heating elements positioned within the channels of said body portion, means for exerting pressure upon the upper side of said body portion, a

platen secured to the inner side of said body portion and having longitudinally extending grooves positioned directly beneath the heating elements, a plurality of individual type adapted to be assembled within the grooves and locking members for the ends of the type to thereby hold the type in assembled position.

2. A branding machine comprising a body portion having longitudinal channels therein opening through its under face, heating elements positioned within said channels, a platen secured to the under side of said body portion and provided with longitudinally extending grooves having undercut side walls, a plurality of type having flanges thereon adapted to slide in the undercut of the walls of the grooves, locking plates for locking a row of type in position and means for exerting pressure upon the upper side of said body portion.

3. A branding device having a body portion, a platen secured to the under side of said body portion, longitudinally extending heating elements positioned between said under side and said platen, said platen having longitudinally extending grooves located beneath said heating elements, a plurality of individual type adapted to be assembled within said grooves, members for locking said type in position, and means for exerting a pressure upon the upper side of said body portion.

4. A branding device comprising a body portion, having a plurality of grooves in its under face, a plurality of heating elements in said grooves, a platen secured to the under side of said body portion and having grooves positioned immediately below said heating elements and provided with undercut side walls, a plurality of type having flanges adapted to slide in the undercut portion of said walls, locking plates having flanges adapted to slide in the undercut portion of said side walls, a manipulating handle for applying pressure to the upper side of said body portion and a heat shield positioned between said handle and said body portion and spaced from both said handle and said body portion.

In testimony that I claim the foregoing I have hereunto set my hand at Milwaukee, in the county of Milwaukee and State of Wisconsin.

WILLIAM C. KRAUSE.
